CLAIM

The ornamental design for a caddy for transporting a portable propane bottle in a horizontal mode, as shown and described.

DESCRIPTION

FIG. 1 is a perspective view of a caddy for transporting a portable propane bottle in a horizontal mode, showing my new design;

FIG. 2 is a front elevational view thereof, the rear elevational view being a mirror image of that shown;

FIG. 3 is a top plan view thereof;

FIG. 4 is a bottom plan view thereof; and

FIG. 5 is a side elevational view thereof, the opposite side elevational, view being a mirror image of that shown.

FIG. 1

FIG. 2

FIG. 3

FIG. 4

FIG. 5
